Primary Examiner — Cynthia M Chin(74) Attorney, Agent, or Firm — Hasse & Nesbitt LLC; W. Charles Ehlers; Daniel F. Nesbitt(57) CLAIM

We claim the ornamental design for a mug handle, as shown and described.

DESCRIPTION

FIG. 1 is a perspective view of the mug handle;
 FIG. 2 is a left side elevation view thereof;
 FIG. 3 is a front elevation view thereof;
 FIG. 4 is a right side elevation view thereof;
 FIG. 5 is a back elevation thereof;
 FIG. 6 is a top view thereof; and,
 FIG. 7 is a bottom view thereof.

The broken lines shown are included for the purpose of illustrating unclaimed portions of the article and form no part of the claimed design.
